UNITED STATES PATENT OFFICE

SIDNEY J. MONK, OF WASHINGTON, DISTRICT OF COLUMBIA, ASSIGNOR TO NORA MONK,
OF WASHINGTON, DISTRICT OF COLUMBIA

ILLUMINATING MEANS

Application filed June 4, 1930. Serial No. 459,198.

One of the objects of the present invention is to provide a novel structure made up of detachable parts, and in which standard electrical lighting equipment may be employed that is adaptable to a wide range of variation in design and involves a structural make-up which can be shipped in knockdown condition and readily assembled by the purchaser, the parts in themselves being simple and easy to manufacture.

In the accompanying drawings:

Figure 1 is a side elevation of one embodiment of the invention illustrating one design the "candle" elements may take.

Figure 2 is a similar view but showing a different design.

Figure 3 is a detail vertical longitudinal sectional view on an enlarged scale through a portion of the structure in order to illustrate the parts thereof and their relation when in assembled condition.

Figures 4 and 5 are cross sectional views respectively on the lines 4-4 and 5-5 of Figure 3.

Figure 6 is a bottom plan view of the holding bar with the channel closure strip removed.

Figure 7 is a vertical sectional view through a slightly modified form of construction.

Figure 8 is a similar view of another modification.

Figure 9 is a cross sectional view of one of the tubular supports.

In the embodiment disclosed in Figures 1-6 inclusive, the fixture is of the pedestal type, including a base member designated generally by the reference numeral 9, carrying a plurality of holders 10 having socket elements 11 for the reception of the usual small electric lamps such as are used for decorative purposes.

The base member consists of a platform 12 on which is a standard 13, and mounted on the upper end of the said standard is a holding bar 14. The three parts 12, 13 and 14 are separable. The standard 13 is mounted on the base 12 by dowels 15 which, however, are preferably not glued or otherwise fastened in place, so that the parts 12 and 13 are readily separable. The holding

bar 14 is provided in its upper side with a plurality of vertical, and therefore, transversely disposed sockets 16. The underside of the bar has a longitudinal channel 17, and this channel is in communication with the bottoms of the sockets 16 through openings 18 of less area than the sockets. Consequently said sockets have bottoms. The rear side of the bar is vertically slotted, as shown at 19, and these slots intersect the channels 17, 60 the sockets 16, and the openings 18 (see Figure 4).

The supports 10 are tubular in form, and have their lower ends seated in the sockets 16, resting on the bottoms thereof. These tubular supports are not cemented or otherwise fastened in the sockets, except as hereinafter explained, and are therefore readily detachable from the bar. The supports constitute simulations of candles. They are longitudinally slotted, as shown at 20. In their upper ends are located electric lamp socket elements 11 having flanges 21 that rest on the upper ends of the said tubular supports 10. In the sockets of these elements are the electric lamps 22.

The socket elements 11 are mounted on and connected to electrical conducting wires 23 and are preferably, though not necessarily coupled up in series. As a consequence one line of wires consists of sections extending from one socket element to the next, and when in assembled condition, these wires extend longitudinally through the supports 10, through the bottom openings 18 of the sockets, and lie in the channels 17. The terminal wires 24 (see Figure 6) leading from the outermost set of socket elements, are brought into the channel 17 and may be extended from the bar through any of the slots 19. The wires 23 are somewhat longer than the length of the supports 10 and the distance between the openings 18. This allows sufficient wire to permit the assembly of the parts. After they are in place the intermediate portions of said wires, which are in the channel 17, are twisted, as shown at 25, thereby drawing the wires 23 taut in the supports 10. The consequence is that the wires 23 serve to hold the socket elements 11 tightly in the upper

ends of the supports 10 and to hold the said supports effectively in their respective sockets 16.

The side walls of the channel 17 (see Figures 4 and 5) are internally and longitudinally grooved, as shown at 26 to slidably receive a bottom closure strip 27 for said channel 17. As a consequence it will be noted that the side walls of the channel extend below the strip 27, forming spaced depending flanges 28. The upper end of the standard 13 engages between the said flanges 28 and is rested upon by the strip 27, as shown in Figure 5. To hold the bar 14 on the standard 13, a dowel pin 29 is inserted in the upper end of the standard 13 and passes through the strip 27, across the channel 17, and into a socket 30 in the bar above said channel and between two of the sockets 16. It will be understood that this dowel 29 is preferably not glued or fastened in place so that the bar 14 and standard 13 can be readily separated. When assembled however, it will be evident that the strip 27 cannot slide in the grooves 26, but is held by the dowel 29.

This structure, as disclosed, has a wide range of adaptability and is of a knockdown character, so that it can be compactly arranged for shipment. More than that, it can be easily set up by the purchaser in a variety of designs. It will be understood that the electrical portion comprising the wiring and socket elements 11 is a standard unit, which can be bought in the open market and is commercially used for Christmas tree lighting. This device in its entirety can be readily placed in the structure and is readily removed. The connecting wires 23 between the socket elements 11 are passed through the slots 19 of the bar and the slots 20 of the tubular supports 10, the said wires being long enough to permit the socket elements 11 being brought over and inserted into the upper or outer ends of the supports. The wires 23 are then drawn downwardly and the closure strip 27 being removed, the wire is twisted, as shown at 25. Consequently said wires, as heretofore explained, perform a triple function, to-wit, 1, a conductor for electric current; 2, a means for holding the socket elements 11 in the supports 10; 3, a means for maintaining the supports 10 in the sockets 16. Having assembled the parts, the closure strip 27 is placed in position, the pedestal structure is assembled, and the bar is mounted thereon. By using supports 10 of different lengths, the design of the structure can be altered in a great many ways. Thus as shown in Figure 1, the longest supports are placed centrally and the others in stepped relation towards the ends, but these may be reversed, for example, as illustrated in Figure 2.

A slightly different modification of the structure is shown in Figure 7. In this case

the platform 31 has removably mounted thereon by means of dowels 32, a standard 33, and on the standard is a holding bar 34. This bar is provided with sockets 35 and channels 36, all as heretofore described. A removable closure strip 37 rests on the standard 33. In this structure but three supports 38 are employed. They are preferably of larger size to hold lamps 39, three of which may be sufficient parallel to be the equivalent of a single ordinary lamp. By reason of the use of three supports, one of the sockets 35 is centrally located. Consequently two dowels 40 are employed between the standard 33 and the bar 34, these being located on opposite sides of the central socket but passing through the strip 37 and securing the same in place as heretofore explained.

Still another embodiment of the invention is illustrated in Figure 8. Therein the platform is designated 41, and has detachably doweled to it, as shown at 42, a standard 43. The holding bar is shown at 44, and in this instance is set at an inclination, the top of the standard 43 being beveled as illustrated at 45 for the purpose. The sockets 46 are also bored at an inclination, but otherwise the structure is substantially the same as that already described and therefore it is believed needs no further exposition.

From the foregoing, it is thought that the construction, operation and many advantages of the herein described invention will be apparent to those skilled in the art without further description, and it will be understood that various changes in the size, shape, proportion and minor details of construction may be resorted to without departing from the spirit or sacrificing any of the advantages of the invention.

What I claim, is:

1. An illuminating device comprising a base member having bottomed sockets, tubular supports that detachably and interchangeably engage in the sockets against the bottoms thereof, a plurality of lamp holding socket elements that abut the free ends of the supports and are removable therefrom, and a plurality of wires to which the socket elements are permanently attached and form therewith a current conducting unit, said base member and tubular supports having means for permitting the introduction and removal of the wires with the lamp sockets attached and the introduction and removal of the latter to and from the supports respectively, the wires connecting the socket elements being sufficiently long to extend through the tubular supports and between the sockets and having a surplus amount to be twisted and thereby act as means to hold the supports in the sockets and the socket elements in the supports.

2. In an illuminating device, a pedestal including a holder having transverse sockets

in its upper side, a longitudinal channel in its lower side having communication with the sockets, a closure for the lower side of the channel slidably mounted on the holder, a standard for the holder, and a pin securing the holder and standard together and engaging the closure.

3. An illuminating device, comprising a holding bar having transverse sockets in its upper side and a longitudinal channel in its lower side, tubular supports in the sockets, socket elements in the tubular supports, wires for the socket elements in the tubular supports and channel, a closure for the channel slidably mounted on the bar, a standard on which the bar is supported, and a dowel extending upwardly from the standard through the closure and into the bar.

4. An illuminating device comprising a holding bar having transverse sockets in its upper side and a longitudinal channel in its lower side, tubular supports in the sockets, socket elements in the tubular supports, wires for the socket elements in the tubular supports and channel, a closure strip for the channel slidably mounted on the bar and located above its lower side, leaving a portion of said channel below the strip, a standard having its upper end fitted into the channel below the strip, and a fastener for the standard passing from the standard through the strip and into the bar.

In testimony whereof, I affix my signature.

SIDNEY J. MONK.
